UNITED STATES PATENT OFFICE.

MARTIN HARDSCOG, OF OTTUMWA, IOWA.

MOUNTING FOR ROCK-DRILLS.

No. 842,654.

Specification of Letters Patent.

Patented Jan. 29, 1907.

Application filed July 12, 1904. Serial No. 216,275.

To all whom it may concern:

Be it known that I, MARTIN HARDSCOG, a citizen of the United States, residing at Ottumwa, in the county of Wapello and State 5 of Iowa, have invented certain new and useful Improvements in Mountings for Rock-Drills, of which the following is a specification.

The object of the present invention is to 10 provide a standard or mounting for rock-drills which shall enable a wide range of adjustment of the drill and increase its range and field of operation.

A second object is to provide means for inwardly projecting the drill as a cut is being made and at the same time enable the drilling-bit to be given a rotary as well as a reciprocating motion, thereby increasing the efficiency of the drill and its speed of operation.

20 A third object of the invention is to provide a rigid support adapted to be set up in tunnels or cuts of varying diameter and shape and to enable the use therewith of a drill of larger diameter and heavier stroke than could be readily operated by hand.

The invention consists in the features of construction and combination of parts hereinafter described and claimed.

In the drawings illustrating the invention, 30 Figure 1 is a view showing the mounting or support having attached thereto two rock-drills, and Fig. 2 a view showing the mounting arranged in upright position and having attached thereto a single drill.

35 The support is constructed of a column or pipe A of suitable length, into the ends of which are loosely inserted screws a of suitable length, the degree of adjustment of the column depending largely upon the length of 40 the screws and their extent of projection, and each of the screws at its end terminates in an abutment a', adapted to contact the walls of a mine-tunnel or other support, and said screws are adapted to be outwardly projected by means of wing-nuts B, which bear 45 against the ends of the column or pipe. The wing-nuts are provided with arms b, which enable their easy rotation, so that after the column or support has been inserted between 50 the walls of a mine-tunnel or between uprights, as shown in Fig. 1, the wing-nuts can be revolved to outwardly project the ends of the screws to force said ends into any crevices or irregularities, thereby firmly anchoring 55 the support preparatory to the drilling operation.

Upon the support are mounted one or more straps or collars C, depending upon the number of drills which it is desirable to operate, and each of said straps or collars terminates in ears c. The ears serve as a mounting for one or more pneumatic drills D, into the smooth-bore tubular shank ends D' of which are inserted feeding-screws d, terminating in tongues d', which are pivoted between the ears by means of pivot-bolts d'', having on their ends nuts d''' for enabling their adjustment. Each of the drills is provided near the rear of the tubular extension or barrel with an arm or handle E for advancing the drill during the drilling operation, and behind the handle is a follower-nut e for locking the drill in position after it has been shoved forward on the feeding-screw by means of the handle E. Air is supplied to 70 the drill through a pipe F, which enters the shank of the feeding-screw d and communicates with a duct F' therein, and to said pipe is attached a rubber hose f for admitting air under pressure, and the flow of said air under 75 pressure is controlled by means of a valve f' or any other suitable means.

The parts heretofore described can be set up as shown in Fig. 2 where the conditions are such as to prevent the adjustment of the 80 standard or support between two side walls or supports, such as shown in Fig. 1. In this case the support A is set upright and the screws a removed therefrom, and one of said screws can be then secured to the upper end 85 of the support by means of one of the collars C, and said screw is then entered into a diagonal brace A', which is provided at its end with a peg a'', adapted to be forced into a crevice in the rock or elsewhere, after which 90 the parts are tightened and adjusted by means of a wing-nut a''', which firmly drives the peg into the ground and forms a firm and rigid support for the standard, enabling the drill to be secured thereto in the same manner heretofore described. When the apparatus is set up in this way, the drill itself by 95 its contact with the rock to be operated upon prevents the forward projection of the standard or column, so that a rigid mounting is 100 provided.

The operation of the device will be partially understood from the foregoing description, but may be briefly stated as follows: After the column has been anchored the collars to which the drills are pivoted are moved 110 along the column to the desired position and

then clamped by tightening the nuts, after which the drill may be swung on its pivot in the arc of a circle until the desired point has been reached for drilling the hole. When 5 such adjustment has been made, the drill will be projected forwardly by moving the handle E, which carries the drill along the screw d until the bit of the drill contacts the point at which the hole is to be made, after which 10 air under pressure is admitted and the drilling operation begins. As the bit advances into the hole the handle is turned, which serves the purpose of revolving the drill to facilitate the drilling operation, and the drill 15 is advanced from time to time by shoving it forward and simultaneously advancing the nut e, which holds it in position and prevents the escape of air along the threads of the feed-screw, the operator using one hand to 20 turn the handle and the other to rotate the follower-nut.

The support is one which provides a wide 25 field of adjustment and range of operation and at the same time enables the use of a powerful drill without the necessity for providing a complicated or cumbersome mounting. By the use of the feed-screw and follower-nut the back kick of the hammer is 30 prevented, which would impair its use mounted, so that the entire force of the hammer is expended on the bit and the drilling operation greatly facilitated.

The device is simple in its operation and 35 may be applied to or used with hammers of any usual and well-known variety, and the length of said hammer and its proportion can be varied without departing in any way from the spirit of the invention.

What I regard as new, and desire to secure 40 by Letters Patent, is—

1. A mounting for rock-drills, consisting of a support adapted to be maintained in suitable position with respect to a fixed abutment, a screw between the support and the 45 abutment, a nut for regulating the pressure exerted by the screw against the support, in combination with a rock-drill having an extension or barrel rigidly secured thereto, a tubular screw-threaded shank adjustably se- 50 cured to the support and entered into the ex-

tension or barrel and provided with a pressure-supply passage leading to its interior, a handle for forwardly projecting the barrel during the drilling operation, and a follower-nut on the screw-threaded shank for locking 55 the barrel and drill in projected position, substantially as described.

2. A mounting for rock-drills, consisting of a tubular support adapted to be held in suitable position with respect to a fixed abutment, a screw slidably mounted in the end of the tubular support and outwardly projecting therefrom, a winged end on the outwardly-projecting portion of the screw and adapted to bear against the end of the tubular support for regulating the position of the screw, a collar adjustable on the support, in combination with a rock-drill having an extension or a barrel rigidly secured thereto, a screw-threaded tubular shank pivoted at one 60 end to the collar and having its opposite end entered into the extension or barrel, a pressure-supply pipe entering the tubular shank for supplying pressure to the barrel, a handle on the extension or barrel for regulating 65 the position of the barrel with respect to the screw-threaded shank, and a lock-nut for holding the barrel and drill in projected position, substantially as described.

3. A mounting for rock-drills, consisting of 70 a tubular support, screws slidably mounted in the ends of the support, winged nuts screw-threaded onto the screws and adapted to bear against the ends of the tubular support for outwardly projecting the screws 75 therefrom, a collar adjustable on the support, in combination with a rock-drill having an extension or barrel rigidly secured thereto, a tubular screw-threaded shank pivoted to the 80 collar and having its opposite end entered 85 into the extension or barrel, an adjustable handle secured to the drill for sliding the barrel along the screw-threaded shank during the drilling operation, and a follower-nut for locking the barrel and drill in projected position, substantially as described.
